UNITED STATES PATENT OFFICE.

CHARLES KIRCHNER, OF SUGAR, IDAHO.

CENTRIFUGAL SUGAR-MACHINE.

1,126,485.

Specification of Letters Patent.

Patented Jan. 26, 1915.

Application filed December 20, 1913. Serial No. 807,858.

To all whom it may concern:

Be it known that I, CHARLES KIRCHNER, a citizen of the United States, residing at Sugar, in the county of Fremont and State of Idaho, have invented certain new and useful Improvements in Centrifugal Sugar-Machines, of which the following is a specification.

My invention relates to improvements in 10 centrifugal sugar machines, and refers particularly to means for moving the stop to permit the plow or scraper to be swung into position for cleaning or scraping the casing of its accumulation.

15 The main object of my invention is the provision of means adapted to be operated by the gate or cover of the receptacle, which will move the stop out of the path of movement of the plow or scraper, and permit it 20 to perform its desired function.

Another object of my invention is the provision of means of the character and for 25 the purpose stated which will operate instantly upon the application of the discharge cover, which will instantly be returned to normal position, and not become accidentally released, and which will be the embodiment of simplicity, durability and 30 inexpensiveness, and which will be thoroughly efficient and practical in every particular.

To attain these objects, my invention consists in certain details of construction, combination and arrangement of parts, substantially as shown, described and claimed herein.

Figure 1 represents a front elevation of 40 portions of a centrifugal machine equipped with my improvement, the parts being in normal position. Fig. 2 represents a sectional view on line 2—2 of Fig. 1. Fig. 3 represents an enlarged sectional view of the stop and retaining means forming the principal part of my invention.

45 Referring by numerals to the drawing, in which similar characters of reference designate corresponding parts in the several views: The numeral 1 designates the casing, 2 the shell or receptacle therein having the discharge opening 3, 4 the cover or gate for the discharge opening, 5 the driving shaft, 6 the mounting or hanger for said shaft, 7 the driving pulley on said shaft, 8 the shaft carrying the plow or scraper 9, 50 and 10 the swinging frame in which the shaft carrying the scraper is mounted, 11

the belt guide, secured in proper relation to the driving pulley by connecting rods 12, one end of which is secured in the mounting at 13, and the other end in the brackets 13; 60 secured upon the belt guide 11. The parts referred to are of well known construction and in connection therewith my invention is employed. Upon one of the connecting rods 12, is secured the block or head 14, in 65 one side of which is mounted the stop bolt 15, having a head 16, and connected thereto the coil projecting spring 17, which spring acts to force the stop bolt outward, in which position it is locked by the spring 70 actuated retaining bolt 18. This retaining bolt is mounted in a passage 19, of the head and its inner end 19' engages a slot 20, in one side of the stop bolt and locking bolt in outward position. To keep the bolt from 75 rotating upon withdrawal of retaining bolt 19, I employ the keeper 21, which has its inner portion engaging a slot 22, in said stop bolt.

The construction referred to is seen most 80 clearly in Fig. 3, which shows the parts in normal position, the stop bolt being retained outward and being in the path of movement of the swinging frame 10, which carries the plow or scraper, as shown in Fig. 85 2. For the purpose of releasing the stop bolt and allowing it to be pushed into the head, I connect with the spring-actuated retaining bolt 18, the rod 23, which leads the angle lever 24, which is pivoted at 25 upon 90 the belt guide and has connected therewith at 26, the upper end of the depending arm 27, which arm is guided in the pair of plates 28 and has the hook 29, at its lower end to receive the discharge cover or gate, 4. The 95 rod 23, forming the connection between the angle lever and spring-actuated bolt 18, is made in two parts connected by an adjusting sleeve 30, which serves to take up any wear or play upon the parts, and also serves 100 to adjust the tension of the spring which actuates the retaining bolt.

When the parts are in normal position, the swinging frame with scraper is in the position shown in Figs. 1 and 2, and when 105 desired to bring said scraper into position for use, the discharge gate is placed upon the hook of the depending arm, the gate, by reason of its weight, drawing upon the arm and tilting the angle which pulls upon 110 the connecting rod, draws the spring-actuated bolt out of engagement with the stop

and allows it to be pushed backward and out of the path of movement of the shaft 8, mounted in swinging frame, thus allowing the scraper to be brought into position 5 for its operation.

On completion of operation the swinging frame and scraper are returned to normal position and discharge gate removed from hook. Immediately the retaining bolt 10 returns to normal position, locking the stop bolt in the inward position to which it has been returned by the action of the coil projecting spring.

I claim:

1. In a centrifugal sugar machine, the combination of a casing, a swinging frame mounted on said casing, a shaft carrying a scraper and mounted in said frame, a shaft mounting above said casing, said driving 20 shaft depending from the mounting into the casing, a belt-guide arranged adjacent said shaft, a depending arm slidably mounted on the belt-guide, and mechanism connected with said arm and actuated by the movement of the arm to permit the swinging of the scraper shaft past the belt-guide.

2. In a centrifugal sugar machine, the combination with a casing, a swinging frame mounted on said casing and a shaft carrying a scraper and mounted in said frame, of a hanger above the casing, a shaft bearing in said hanger, a belt-guide supported from said hanger, a depending arm slidably mounted on said belt guide and having a hook at its lower end, an angle lever fulcrumed on the belt guide and having one end connected to the depending arm, and mechanism connected with the other end of said angle lever and actuated by the movement of the arm to permit the swinging of the scraper shaft past the belt guide.

3. In combination with a shaft-mounting, a driving shaft, a belt-guide secured to said shaft mounting, an arm depending from said 45 belt-guide and movable therein, an angle

lever pivoted to the belt-guide and connected with said arm, a head carried by the belt guide and shaft mounting, a spring actuated stop bolt mounted in said head, a spring actuated retaining bolt in the head engaging 50 the stop bolt, and a connection between said bolt and angle lever.

4. In a centrifugal sugar machine, the combination with a casing having a discharge opening, a swinging shaft carrying 50 a scraper, of a hanger above said casing, a driving shaft mounted in said hanger and depending into said casing, a belt guide supported from the hanger, an arm movable in the belt-guide and having a hook and 60 mechanism connected with said arm and actuated by the movement of the arm to permit the swinging of the scraper shaft past the belt guide.

5. In a centrifugal sugar machine, the 65 combination with a casing having a discharge opening, a swinging shaft carrying a scraper, of a hanger above said casing, a driving shaft mounted in said hanger and depending into said casing, a belt guide supported from the hanger, an arm movable in the belt-guide and having a hook and mechanism connected with said arm and actuated by the movement of the arm to permit the swinging of the scraper shaft past the belt- 70 guide, said mechanism consisting of an angle lever carried by the belt guide having one end connected with the arm, a rod leading from its other end, a retaining bolt connected with the other end of said rod, a 80 stop bolt engaged by said retaining bolt, and a head supported by the belt guide and hanger and carrying said retaining and stop bolts.

In testimony whereof I affix my signature 85 in presence of two witnesses.

CHARLES KIRCHNER.
